UNITED STATES PATENT OFFICE.

ROBERT F. ADAMS, OF BIRMINGHAM, ALABAMA.

ELECTRIC JAIL-ALARM.

SPECIFICATION forming part of Letters Patent No. 741,992, dated October 20, 1903.

Application filed March 6, 1903. Serial No. 146,539. (No model.)

To all whom it may concern:

Be it known that I, ROBERT F. ADAMS, a resident of Birmingham, in the county of Jefferson and State of Alabama, have invented 5 certain new and useful Improvements in Electric Jail-Alarms, of which the following is a specification.

This invention relates to jail-alarms specially adapted for indicating, at the warden's 10 room or separate building in which he may reside, tampering with or severing of the jail-window grating by the prisoner in his attempt to escape by breaking or sawing the bars of the window-grating.

15 The invention consists, broadly stated, in peculiar electrical wiring of the jail-window grating whereby breaking or sawing of either of the bars forming the window-grating will break or sever the wiring and cause an alarm 20 to sound by means of suitable circuit-wires thereby put in electrical circuit with the alarm.

The invention comprehends, in connection 25 with each wire employed in connection with the window-grating, a peculiar circuit-closer and also novel means whereby all the wires extending from the circuit-closers just mentioned are effectively protected from each window of the jail to the warden's room or 30 separate building in which he may reside.

The invention also comprehends the employment of some suitable annunciator, alarm-bell, and battery located in the warden's room or separate building having electrical 35 connection with all the wires leading from the grating-bars of all the windows in the jail and the annunciator adapted to indicate which window-grating is being tampered with and also which bar in the window 40 grating is being cut, broken, or tampered with.

The invention also comprehends special normally open circuit-closers with each wire employed in connection with the bars of the 45 several window-gratings which when cut or broken automatically complete an electrical circuit with the alarm-bell and the annunciator, the latter indicating by suitable well-known means the window and bar thereof 50 being cut or broken.

A still further novelty resides in special means employed by me whereby the alarm-

bell is caused to sound until the severed wire of the window-grating is connected or restored to original condition adapted to hold 55 its circuit-closer to open or normal position.

In order to enable others to make and use my invention, I will now proceed to describe it in detail with reference to the accompanying drawings, which form a part of this specification. 60

In the drawings, Figure 1 is a view showing the exterior of a jail having one window. The view also shows a remotely-located building in which the jail warden may reside and 65 wiring extending from the jail-window in circuit with an annunciator and alarm-bell located in the warden's residence. Fig. 2 is an enlarged detail sectional view taken horizontally through the jail-wall and switch-box. 70 The view also shows in section one end of a window-grating bar with its interior wire projecting therein. Fig. 3 is a detail plan view of my switch-box, showing its circuit-wires leading therefrom through a suitable protecting-tube. Fig. 4 is a horizontal sectional 75 view taken through one grating-bar, portion of the wall adjoining the window, and one end of the switch-box; and Fig. 5 is a view showing in front elevation an annunciator with 80 an alarm-bell and battery in electrical circuit with the switch-box circuit-closing devices. Fig. 6 is a diagrammatic view illustrating the 85 circuit-wiring of two window-bars, with the bar and window indicators and also the bell.

I have hereinbefore stated the object of my invention and briefly referred in general terms to leading features thereof; but before describing it in detail I would state that the wiring, switch-boxes, circuit-closers, and 90 window-grating construction, &c., being identically the same at all windows of the jail I deem it sufficient for a full understanding of my invention to describe and show in my drawings only one jail-window with the wiring thereof, the annunciator and alarm employed, and switch device and circuit-wires all arranged and adapted according as invented by me. In this application I do not seek to claim any special arrangement of 95 window-grating or peculiar circuit-closer and annunciator devices, since the same may be varied without departing from the spirit of 100 my invention.

Having now stated the nature of my invention and referred in general terms to the object had in view, I will proceed to describe it in detail as follows:

- 5 In carrying out my invention I employ window-grating of any approved and suitable configuration having in its structure substantially upright and horizontal tubular bars A, whose ends may be embedded in the 10 wall B of the building, as shown in Figs. 2 and 4, or be secured in any other way or position adapted to provide security against removal from the inside of the jail. In all the tubular bars A, I arrange a wire C, having one end thereof fixedly secured at one 15 end of the bar by any approved means. In Fig. 4 I illustrate one means adapted for the purpose, in which an anchor-pin D is employed, with this end of the wire secured thereto. It will be noticed (see Figs. 2 and 4) 20 that the wire C extends from its anchored end, as at D, within and through the bar A, the opening E in the wall B, and thence into a box F, which is provided with a hinged 25 cover G, adapted to be secured by lock and key, as indicated at H, Fig. 1. Within the box G, I arrange a suitable normally open switch or circuit-closer H. (See Fig. 2.) The member I of this switch is formed of an up- 30 right yielding standard having any suitable support on the bottom of the switch-box and constitutes one pole or terminal of the circuit-wires. The member J, constituting the other pole or terminal, is formed of a ring at 35 the upper end of an arm J', as shown in Fig. 2. A spring M, having one end suitably connected with the far inner side wall of the box F, as at N, has its other end made fast to the ring L, to whose opposite side the wire 40 C is secured. (See Figs. 2 and 3.)
- O indicates inclosing tubes leading from all the switch-boxes F to a common larger inclosing tube P. The latter tube is intended to extend down underground and along into 45 the warden's room Q, as shown in Fig. 1. The object of the inclosing tubes O and P is to provide effective protection for all the circuit-wires leading from the switch-boxes to the warden's room.
- 50 In the warden's room I arrange an annunciator R and alarm-bell S. Annunciators and internal devices thereof being well known to the skilled, it becomes only necessary for me to say that the particular annunciator 55 which I employ is divided into sections 1, 2, or more, (see Fig. 5,) indicating the several windows of the jail and each section having an indicator T of approved and well-known form in circuit and adapted through common 60 electrical means to indicate the window through which the prisoner is attempting to escape. I also provide each section of the annunciator with indicators U similar to the window-indicator T and with each of the 65 said indicators U in circuit with the poles of one circuit-closer H and also the alarm-bell S. In other words, the wiring and operating

devices of the bell and indicators may be ordinary, as will be suggested to those skilled in the art, and operate, when one switch H is closed, its indicator U, and the window-indicator T. Obviously the bell S should be in circuit with all the indicators U of the several sections on the annunciator.

V indicates a battery which may be located 75 in the warden's room in circuit with all the indicators on the annunciator and the alarm-bell.

W indicates circuit-wires leading from all the switches H to the annunciator through 80 the small tubes O and the common tube P.

I do not deem it necessary to show or describe any particular wiring or means within the annunciator for working the several indicators, since the wiring and devices that I 85 use are well known and now employed with annunciators in telephones and other electrical systems.

With all the parts and circuit-wires arranged as above stated the operation would 90 be as follows: Should a prisoner in the jail attempt to escape by sawing through one of the bars A, he would cut the wire C. With the wire C cut or broken loose at its anchored end obviously the spring M would be free to 95 pull back on the ring L, and thereby draw the terminal I to the dotted position *a* in contact with the terminal J. This action would close the circuit at the switch H between the battery U, the bell S, the window-indicator 100 T, say, in section 1, and the grating-bar indicator V in that section of the annunciator. Obviously simple bending of the grating-bar A, as shown in Fig. 3, would draw on the spring M and adjust the standard I, as indicated by dotted position *b*, and thereby 105 complete the circuit, as will be understood. When a circuit is closed as just described, the bell will continue to sound until the wire C is restored to original or anchored condition through the tube A, with the spring M under tension and the standard I out of contact with the ring-terminal J.

The electrical features of my invention may be tested from time to time by unlocking and opening the door G of the switch-box and moving the standard-terminal I to the dotted position *b*, thereby closing the alarm and annunciator circuits.

Having thus described my invention, what 120 I claim as new, and desire to secure by Letters Patent, is—

1. In a jail-alarm and in combination, window-grating having tubular bars, a wire in the said tubular bars having one end fixedly anchored and its other end yieldingly secured, a normally open switch at the yielding end of the said wire, means at said yielding end of the wire whereby the switch may be tested, means operating to close the switch upon movement of the said yielding end of the wire in one of opposite directions, an annunciator including a battery and alarm-bell, and a series of indicators on the annunciator

with one indicator of the series in circuit and adapted to operate at the same time with either other indicator of the series and also the alarm-bell, the poles of each normally open switch, the several indicators on the annunciator, and the bell, being in circuit with the annunciator-battery, substantially as described.

2. In a jail-window grating employing tubular bars, and in combination, a wire in the said tubular bars having one end fixedly anchored and its other end yieldingly secured, a switch-box adapted to receive and contain the yielding end of the said wire, a normally open circuit-closer in said switch-box, also yielding means therein connecting this end of the wire and the circuit-closer and whereby upon movement of the circuit-closer connection in one of opposite directions, the circuit is closed, an alarm-bell, battery circuit, and annunciator as specified, indicators arranged in sections on the annunciator, with one indicator, in each section, in circuit with

each other indicator in its section and also the alarm-bell, and wires in circuit with the annunciator and bell operating devices and the said circuit-closer in the switch-box, substantially as described.

3. The combination in a jail-alarm of the character described, employing inclosed wires across the jail-window, circuit-wires, an annunciator, bell, and battery circuit as specified, of an inclosed normally open circuit-closer at one end of the said wires across the jail-window, means in the switch-inclosure adapted to hold the adjacent end of said wire under tension and also operate the circuit-closer when that portion of the wire across the window is cut or bent, and means whereby the annunciator, bell, and battery circuits may be tested, substantially as described.
